RADIANT TUBE FURNACE

James C. Woodson, Cleveland, Ohio, assignor to
 Lee Wilson Sales Corporation, Cleveland, Ohio,
 a corporation of Ohio

Application January 16, 1939, Serial No. 251,131

7 Claims. (Cl. 263—42)

This invention relates to a furnace and, in particular, to a furnace adapted to be heated by radiation from heat-exchange tubes mounted interiorly thereof for conducting hot combustion gases or other fluid heating medium.

Numerous types of radiant tube furnaces have been proposed heretofore and it is the general object of this invention to improve upon such furnaces as previously constructed.

10. The invention is concerned particularly with a novel form of heat-exchange tube of such construction as to provide better fuel economy than has been obtainable with the heat-exchange tubes now in use. A further object of the invention 15 is to provide a tube having a longer useful life than the tubes now in use and, furthermore, to provide a tube which may be readily fabricated at relatively low cost.

In a preferred form of the invention, I provide 20 a heat-exchange tube having substantially parallel branches or passages and preferably mount it adjacent a wall of the furnace. To the discharge end of the tube, I connect an exhaust flue embedded in the furnace wall. I also provide a 25 connection from the discharge end of the tube to the entrance thereof to permit a small portion of the combustion gases to be induced into the stream of freshly burning gases for re-circulation therewith.

30. Further details of the embodiment outlined above will be explained herebelow with reference to the accompanying drawing in which

Fig. 1 is a transverse sectional view through a furnace having the invention incorporated there- 35 in;

Fig. 2 is a partial sectional view taken substantially along the plane of line II—II of Fig. 1; and

Fig. 3 is a sectional view through the heat-ex- 40 change tube alone along the plane of line III—III of Fig. 1.

Referring now in detail to the drawing, I have 45 illustrated therein a furnace 10 of the cover type merely as a convenient example since the invention may be applied to various types of furnace structures. The furnace 10 includes a cover 11 removably disposed on a base or hearth, a portion of which is shown at 12. The cover 11 is open at the bottom and comprises side walls, end walls and a roof of refractory material as- 50sembled within a structural frame 13 and sheathing plates 14. The base 12 is built up from refractory material assembled on any suitable supporting foundation. The base is adapted to support a charge of material 15 such as a stack of 55 sheets or coil of strip to be subjected to process-

ing, e. g. annealing. The base is also provided with a sealing channel 16 adapted to receive the lower edge of an open-bottomed protective cover 17 fabricated from light plate. The base 12 also has a shoulder or margin 18 adapted to receive 5 the bottom edge of the side and end walls of the cover.

Heat-exchange tubes 19 are mounted interiorly of the furnace and may conveniently be disposed in spaced relation along the side walls of the 10 cover. The tubes 19 may be of any convenient construction but I prefer a tube of substantially oval section, the lower end of which is disposed substantially at right angles to the main body of the tube, as indicated at 20. This portion of 15 the tube traverses the furnace wall and is embedded therein.

As shown, the tubes 19 are disposed with their longer portions 21 vertical although they may be disposed at any convenient angle. A central longitudinal partition 22 disposed in each tube divides it into a pair of substantially parallel pas- 20 sages or branches 23 and 24. A cross wall 25 substantially in line with the partition 22 divides the lower portion 20 of the tube and, with the 25 partition, constitutes a baffle extending from the bottom of the tube to a point spaced below the top thereof, thereby establishing communication between the passages 23 and 24 at their upper ends. A port or opening 26 is formed in the 30 cross wall 25 for a purpose which will appear shortly.

A burner 27 extends into the side of the bottom portion 20 of the tube which is in communication with the passage 23. The other side of 35 the portion 20 terminates in the side wall of the furnace and does not extend outwardly there- 40 through, the outer end of this portion being indicated at 28. A spark gap igniter 29 is disposed adjacent each burner and is connected to an en- 45 ergizing transformer 30. A manifold 31 extends along each side of the furnace for supplying to the burners a combustible mixture of air and gas.

The side of the lower portion 20 of each tube opposite that into which the burner 27 extends, 45 indicated at 32, has an opening 33 at the top thereof. An exhaust flue 34 embedded in the fur- 50 nace wall fits down over the opening 33. The exhaust flue serves to carry waste gases upwardly through the furnace wall and to the exterior at- 55 mosphere for discharge. This construction has a particular advantage in that the waste gases contain a substantial amount of heat even after traversing the passages 23 and 24. A portion of this remaining heat content of the exhaust gases 55

is absorbed by the brickwork composing the furnace wall, thereby making up at least in part, the heat lost from the exterior of the walls.

The operation of the furnace of my invention will now be explained briefly. It will be understood that the covers 11 and 17 are raised to permit the charge 15 to be initially placed on the base 12. The covers are then replaced as illustrated. A combustible mixture such as fuel gas and air in proper proportions is supplied to the manifolds 31 under the control of suitable valves in a supply main and the mixture issuing from the burners 27 is ignited by spark gaps created by energizing the igniter points 28. It will be understood, of course, that where the furnace is employed in continuous processing, the burners remain ignited and it is necessary to energize the igniter points only when starting up.

After ignition, the combustible gases burn as they traverse the passages 23 and 24. After passing around the upper end of the partition 22 and descending through the passage 24, the combustion gases having given out most of their heat to the walls of the tubes 19, enter the portions 32 of the lower ends of the tubes and thence pass upwardly through the openings 33 and through the exhaust flues 34. A small portion of the combustion gases which have traversed the passages 23 and 24 is induced through the opening 26 in the cross wall 25 into the stream of freshly burning gases ascending from the burner through the passage 23. This re-circulation of a portion of the combustion products tends to eliminate substantial differences between the temperatures of different parts of the tube by cooling the gases slightly in the initial stages of combustion. This reduces erosion of the tube in the area on which the flame jet impinges and thereby lengthens the useful life of the tubes. As previously pointed out, as the combustion gases ascend through the exhaust flue 34 they give up a certain portion of their heat to the furnace walls, thereby making up at least in part, the heat lost from the exterior of the walls, and increasing the overall thermal efficiency of the furnace. It will be noted that while the shape of the flues 34 in section is different from that of the passages 23 and 24, the dimensions are such that the sectional areas are approximately the same at all points along the path of the gases.

After the charge 15 has been heated to the proper temperature, the cover 11 is removed and disposed on another previously loaded base, the cover 17 being left in place to protect the charge during the slow cooling thereof.

It will be apparent from the foregoing description and explanation that the invention provides a radiant tube furnace having numerous advantages over furnaces of this type previously available. In the first place, a relatively long path is afforded for the combustion gases which increases the amount of heat given out by them to the surrounding heat-conducting walls of the tube. Re-circulation of a portion of the combustion gases tends to make the temperature of all portions of the tube substantially uniform. The economy obtained by leading the exhaust gases through flues embedded in the furnace walls has already been mentioned.

A further advantage of the invention is that the tubes 19 are specially adapted for burning pre-mixed air and gas which also contributes to a high thermal efficiency.

Although I have illustrated and described but

it will be understood that numerous changes and modifications therein may be made without departing from the spirit of the invention or the scope of the appended claims.

I claim:

1. In a furnace having a side wall and a roof, a heat-exchange tube disposed substantially vertically adjacent said wall, said tube being substantially oval-shaped in section and having a baffle extending longitudinally therethrough providing a pair of substantially parallel gas passages and having a portion at its lower end disposed substantially at right angles to the remainder of the tube, said portion extending into said wall, and an exhaust flue extending upwardly within said wall from the lower end of said tube and communicating with one of said passages.

2. In a furnace having a side wall and a roof, a heat-exchange tube disposed substantially vertically adjacent said wall, said tube providing a pair of substantially parallel gas passages and having a portion at its lower end disposed substantially at right angles to the remainder of the tube, said portion extending into said wall, and an exhaust flue embedded in said wall and extending upwardly therein, said flue communicating with one of said passages at the lower end of the tube.

3. In a furnace having a side wall and a roof, a heat-exchange tube disposed substantially vertically adjacent said wall, said tube providing a pair of substantially parallel gas passages and having a portion at its lower end disposed substantially at right angles to the remainder of the tube, said portion extending into said wall, one of said passages terminating within the wall and being open at the top whereby it communicates with an exhaust flue extending upwardly therefrom within the wall.

4. In a furnace including a base adapted to support a charge of material to be heated and a heating cover adapted to be positioned on the base, heating means carried by said cover comprising a plurality of heat-exchange tubes mounted interiorly of said cover, each tube comprising a burner portion extending through the cover below the top of said base when the cover is positioned thereon and adapted to receive a burner therein, a vertical heat-exchange portion extending upwardly from said burner portion, a second heat-exchange portion substantially parallel to the first and communicating therewith at the upper end thereof, an outlet portion communicating with the lower end of said second heat-exchange portion and extending outwardly therefrom below the top of said base when the cover is positioned thereon, and a stack communicating with each outlet portion and extending upwardly therefrom.

5. In a furnace including a cover having side walls and a roof and a base, a heat-exchange tube disposed substantially vertically adjacent said wall, said tube providing a pair of substantially parallel gas passages and having a portion at its lower end disposed substantially at right angles to the remainder of the tube, said portion extending into said wall below the top of said base when the cover is deposited thereon, and an exhaust flue extending upwardly along said wall from the lower end of said tube and communicating with one of said passages.

6. In a furnace having a side wall and a roof, a heat-exchange tube disposed substantially vertically adjacent said wall, said tube being sub-

stantially oval-shaped in section and having a baffle extending longitudinally therethrough, providing a pair of substantially parallel gas passages and having a portion at its lower end disposed substantially at right angles to the remainder of the tube, said portion extending into said wall, an exhaust flue extending upwardly along said wall from the lower end of said tube and communicating with one of said passages, 5 and a burner extending into the other passage, said baffle having a bleeder port adjacent said burner.

7. In a furnace having a side wall and a roof, a heat-exchange tube disposed substantially vertically adjacent said wall, said tube providing a pair of substantially parallel gas passages, a burner supplying combustion gases to one of said 5 passages, and an exhaust flue connected to the other passage at the lower end of said tube and embedded in said wall.

JAMES C. WOODSON. 10
